Primary Examiner — Sandra Snapp(57) **CLAIM**

The ornamental design for a latch for a case, as shown and described.

DESCRIPTION

FIG. 1 is a front isometric view of a latch for a case showing our new design;

FIG. 2 is a rear isometric view thereof;

FIG. 3 is a front view thereof;

FIG. 4 is a left view thereof;

FIG. 5 is a right view thereof;

FIG. 6 is a top view thereof; and,

FIG. 7 is a bottom view thereof.

The broken lines immediately adjacent the shaded surfaces represent boundaries of the claimed design. All other broken lines depict unclaimed environment. The broken lines and unshaded regions bounded by the broken lines form no part of the claimed design.
